UNITED STATES PATENT OFFICE.

THOMAS J. CLARKE, OF JAMESTOWN, NEW YORK.

LABEL-HOLDER.

1,286,943.

Specification of Letters Patent. Patented Dec. 10, 1918.

Application filed August 1, 1918. Serial No. 247,819.

To all whom it may concern:

Be it known that I, THOMAS J. CLARKE, a citizen of the United States, residing at the city of Jamestown, in the county of Chautauqua and State of New York, have invented certain new and useful Improvements in Label-Holders, of which the following, taken in connection with the accompanying drawings, is a specification.

10 The invention relates to cabinets or receptacles for labels such as are commonly used by druggists and others, the present construction being a continuation of the label holding cabinet construction shown in my 15 Patents Nos. 1,065,112 and 1,065,293, bearing date June 17th, 1913; and the object of the improvement is to provide a simple construction which is adaptable to sheet metal in which the labels are held in inclosing adjustable guides within the drawer or compartment, being pressed against the front end and a roller across the front end of said guide by a spring plunger; and the invention 20 consists in the novel features and combinations hereinafter set forth and claimed.

In the drawings, Figure 1 is a perspective view of a multiple drawer label cabinet having the improved construction.

Fig. 2 is a perspective view of one end of 30 a drawer showing the labels in position within the hooded guide for said labels.

Fig. 3 is a sectional view at line X X in Fig. 2, showing the combination and arrangement of the parts with the labels in 35 position therein.

Fig. 4 is a perspective view of a corner of the label holding receptacle with the hooded guide and the drawer in section, a portion of the guide and drawer being broken away, 40 and showing the guide rod for the presser plate and hooded guide; and Fig. 5 is a lengthwise sectional view of a portion of the drawer with guides therein, showing the arrangement of the same.

Fig. 6 is an elevation of the roller in the front end of the label guide with the sides of said guide in section, showing the simple manner in which the roller is journaled in said sides.

Fig. 7 is a plan view of a drawer from a label cabinet showing the arrangement of the different label holding guides.

Fig. 8 is a perspective view of the plunger or presser plate for holding the labels in position and pressing them against the drawer end and roller.

Fig. 9 is a perspective view of the hood or guide for the labels.

Fig. 10 is an elevation of the rear end of the rod for the presser plate; and Fig. 11 is 60 a perspective view of the keyhole slot in the back plate of the guide, into which the rear end of the presser plate rod is inserted.

Fig. 12 is a front elevation of a single label holding receptacle.

Like numerals of reference refer to corresponding parts in the several views.

The numeral 10 designates the case or cabinet which is preferably made of sheet metal, although any other suitable material 70 might be used and not depart from my invention.

The numeral 11 designates the drawer of a multiple label cabinet, which drawer is of suitable size and has the upper portion of 75 the front end open, a closure strip 12 for the lower portion of the front end being attached firmly to the bottom and lateral sides of the drawer, against which strip the lower portion of the labels 13 are pressed.

The labels 13 are held in place in the drawer 11 and guided by means of a guide plate or hooded channel piece 14 which is pivotally hinged on a rod 15 extending through the rear portion of the drawer 11. 85 The rear end 16 of the hood 14 is formed at a forward incline so that the front end of the hood 14 may be raised to permit the insertion of the labels 13, and the rod 15 preferably extends through the lower portion or 90 point 17 of the rear end of the hood 14. The rear end of the hood 14 is closed and a lug 14' integral with the closure plate for the rear end of the hood 14 extends down into a groove 23 and has a keyhole slot 25 therein 95 lengthwise of the lug 14' for a purpose hereinafter set forth.

The lower edges of the hood 14 preferably incline upward toward the front end from the points 17 so as to work freely above the 100 partial closure strip 12 for the front end of the drawer 11 and provide inclosing sides for the ends of the labels 13. A finger notch 18 is provided in the front end of the hood 14 to permit access to the first label in withdrawing the same. A roller 19 is journaled in the punched openings 20 in the sheet metal sides of the hood 14. This construction provides a simple and durable bearing for the journals of the roller.

The labels 13 are pressed against the front end 12 and the roller 19 by means of a spring

21 mounted on a rod 22, which rod is placed in a groove 23 in the bottom of the drawer 11 extending from front to rear of said drawer. The guide rod 22 has an annular 5 groove 24 near its rear end for the insertion of said rear end of the guide rod into the keyhole slot 25 in the lug 14' of the hooded guide 14, the grooved end 24 fitting within the slotted portion of the keyhole slot 25 10 and firmly holding the rear end of the rod 22.

A presser plate 26 is provided which is of sufficient size to press against the rear side of the labels 13 and fit within the hood 14. 15 The plate 26 has a downward projection 27 and the rod 22 is slidably mounted within and extends through the tube 28 and plate 26. The coil spring 21 extends between the lug 14' of the guide 14 and the presser plate 20 26 passing over the tube 28, thereby giving a spring pressure to both the presser plate 26 and the hinged hooded guide 14 as its front end rests upon the front labels 13, since the pressure of the coil spring 21 is 25 against the lug 14' at its rear end, and the backward pressure on the lug 14' would obviously give a downward pressure on the front end of the pivotally mounted guide 14.

The assembly of the parts is simple. The 30 hoods or guides 14 are provided in the drawer 11 according to the size desired for the labels so as to fit freely over the same, the spring pressure of the sheet metal hood 14 holding the front labels down in place. 35 For this purpose the top of the hood 14 is preferably inclined at a downward angle toward the front labels so as to press upon said front labels and hold them in place and so that only the label withdrawn will 40 be displaced.

The hood or hoods 14 are pivotally mounted in the single or multiple drawer by inserting the rod 15 through holes in the drawer sides and through holes in the points 17 of 45 the hoods 14. In a long drawer one or more central partitions 29 may be provided to hold the rod 15 firmly in line so that the hooded guides 14 for the labels will be firmly held in line when they are hinged 50 thereon.

Any suitable sheet metal plate construction may be used in the construction of the drawer 11 but provision should be made in the attachment of the bottom of the drawer 55 11 so that room for the grooves 23 is provided. The grooves 23 are preferably bent in the drawer bottom before the attachment of the same to the drawer.

The rods 22 are inserted in the keyhole 60 slots 25, the annular groove 24 permitting the rod to slip downward in the slot and engage the lug 14' in said groove 24. The coil spring 21 is then slipped onto the rod 22 and the presser plate 26 follows the 65 spring 21, after which the front end of the

rod 22 may be dropped into the groove 23, the lower edges of the plate 26 resting upon the bottom plate of the drawer 11 each side of the groove 23.

It is now obvious that the hood 14 may 70 be raised and the labels 13 inserted beneath the same, the presser plate 26 being pressed back sufficiently to permit the insertion of the pack of labels in the front portion of the hood 14 and drawer, after which the hood 75 14 is dropped onto the labels thereby confining and guiding them with the presser plate 26 pressing them against the front end 12 and the roller 19.

The finger notch 18 provides a convenient 80 opening through which the front labels may be easily reached and withdrawn one by one, and the spring pressure of the guide 14 on the tops of the front labels holds said labels firmly in line so that they may be 85 withdrawn a label at a time separating perfectly from the adjacent label as they are drawn over the roller 19.

It is apparent that the keyhole slot 25 might be made in the rear plate of the 90 drawer 11 and the gravity pressure or weight of the hood 14 would serve a fairly good purpose in holding the labels in line but the spring pressure on the hooded guide is preferred since it insures the degree of pressure 95 needed to hold the labels firmly in place.

I claim as new:—

1. A label holder comprising a receptacle having an open front to extract labels there-through, the bottom of said receptacle having a groove from front to rear thereof, a presser plate having a lug extending into said groove, a hooded cover for the labels having a lug extending into said groove, a 105 rod supported on said lugs, and a spring on said rod between said lugs to give a resilient pressure on the labels by both said presser plate and said hooded cover.

2. A label holder comprising a receptacle 110 having an opening across the upper portion of its front end, a groove in the bottom of said receptacle extending from front to rear thereof, a rod in said groove, a guide plate hinged in said receptacle, a lug on said guide 115 plate extending down into said groove around said rod, said guide plate extending over the labels and having downwardly extending sides to hold the labels in line, a presser plate having a lug extending into 120 said groove around said rod resting against the rear side of the labels, and a spring on said rod in said groove between said lugs on said presser plate and guide plate to give resilient pressure to both of said plates 125 and press said plates on said labels.

3. A label holder comprising a receptacle having the upper portion of the front end open, the bottom of said receptacle having a groove extending from front to rear there- 130

of, a presser plate for the rear side of the labels having a lug extending into said groove and a tube on said lug, a guide plate for the labels hinged in said receptacle, a 5 lug on said hinged guide plate extending into said groove and having a keyhole slot therein, a rod having an annular groove around one end for insertion in said keyhole slot and extending near the front end of 10 said groove and inserted through said tube and presser plate, and a coil spring on said rod extending from said presser plate to said lug on said hinged guide plate to give resilient pressure to both said plates to press 15 said plates on said labels.

4. A label holder comprising a receptacle having an opening across its front end, a strip across the lower portion of said front to receive the lower edge of the labels there- 20 against, the bottom of said receptacle having a groove extending from front to rear of its central portion, a presser plate for the rear side of the labels having a lug extending into said groove and a tube on said lug, 25 a hooded guide plate having a top to rest

on the front labels and sides to hold the labels therein, a rod extending through the rear portion of the sides of said hooded guide plate and supported in said receptacle to pivotally support said hooded guide plate 30 a roller revolvably mounted across the front end of said hooded guide plate in the sides thereof a spaced distance beneath the top thereof to withdraw the labels thereover, a lug on said hooded guide plate extending 35 into said groove and having a keyhole slot therein, a rod having an annular groove a spaced distance from one end for insertion in said keyhole slot, said rod extending through the tube in said presser plate, and 40 a coil spring on said rod between said presser plate and hooded guide plate in said groove to give a resilient pressure to both of said plates.

In testimony whereof I have affixed my 45 signature in the presence of two witnesses.

THOMAS J. CLARKE.
